(57) **CLAIM**

The ornamental design for a liner engaging member for a trashcan, as shown and described.

DESCRIPTION

FIG. 1 is a front elevational view of a liner engaging member for a trashcan of the present invention;

FIG. 2 is an enlarged front elevational view thereof;

FIG. 3 is a perspective view thereof;

FIG. 4 is a top plan view thereof; and,

FIG. 5 is a side view thereof.

The broken line(s) which define the bounds of the claimed design form no part thereof.

The broken line showing of a trashcan is included for the purpose of illustrating environment and forms no part of the claimed design.
